UNITED STATES PATENT OFFICE

2,169,755

BURNER FOR LIQUID FUEL

James L. Breese, Santa Fe, N. Mex., assignor to
Oil Devices, Santa Fe, N. Mex., a limited partnership of Illinois

Original application February 8, 1937, Serial No.
124,695. Divided and this application September 11, 1937, Serial No. 163,370

6 Claims. (Cl. 158—91)

My invention relates to an improvement in burners for burning liquid fuels, such as hydrocarbons, and has for one purpose the provision of a burner which can be turned down to a very small fire, or low draft, without destroying the characteristic mode of combustion described, for example, in my prior issued Patent No. 1,702,929, issued on February 19, 1929.

Another purpose is the provision of means for permitting low draft burning with such a burner, while preventing down drafts from upper portions of the combustion chamber, which would disadvantageously affect combustion.

Another purpose is the provision, in connection with one of my burners, of a lower supplementary burner which may have the functions of a pilot light for maintaining combustion during periods when a minimum heat or no heat is desired.

Other purposes will appear from time to time in the course of the specification and claims.

The present application is a division of my application Serial No. 124,695, filed February 8, 1937.

I illustrate my invention more or less diagrammatically in the accompanying drawing wherein:

Figure 1 is a vertical axial section; and

Figure 2 is a section on the line 2—2 of Figure 1.

Like parts are indicated by like symbols throughout the specification and drawing.

Referring to the drawing, 1 generally indicates an outer furnace or heater shell having a combustion chamber 2 spaced therefrom by a horizontal partition 3 provided with a central aperture 4. 5 is a preferably removable upper baffle with a central aperture 6. The combustion chamber or mixing chamber is herein shown as cylindrical with a bottom 8 which may be formed if desired in one piece with the side walls 2 and may be secured in any suitable fashion to the member 3. 10 is any suitable fuel supply pipe extending to the bottom 8 or positioned to deliver fuel thereto. The means for supplying the fuel is not herein shown since it does not of itself form part of the present invention, but it will be understood that any suitable float chamber or the like may be employed for governing the desired flow of fuel, for example a liquid hydrocarbon, to the bottom 8.

11 is a closure member secured within the shell 1 provided with an aperture 12 which may be closed by a separate removable plate 13 which in turn may have a plurality of apertures 14. I illustrate the outer shell 1 as mounted upon legs 15 which space it upwardly from the floor and permit air to flow through the apertures 14 and

thus enter the space between the members 1 and 2.

The member 2 is provided with an upper row of secondary air inlet apertures 16 herein shown as upwardly and inwardly inclined. A plurality of preferably smaller apertures 17 are shown as arranged in rows in the lower portion of the member 2. The bottom row 18 is also indicated. Positioned above the bottom row 18 and below the lowest of the rows 17 is a fixed baffle 19 having a central aperture 20. Mounted partially to close the central aperture is a baffle ring 21 herein shown as rotatable about a horizontal axis defined by the rod 22 journaled in the bearing 23 and the rod 24 journaled in the bearing 25. The rod 24 has an outwardly extending portion 26 terminating in a manually controllable handle 27. The baffle 21 is provided with a central aperture 28.

When a minimum aperture is desired, the parts 20 are positioned in the full line position of Figure 1, which position is also indicated in Figure 2. When a maximum aperture is desired, the operator rotates the handle 27 and thereby moves the baffle 21 into the dotted line position of Figure 1. 25 When in the first position the aperture 28 is the only connection between the portion of the chamber below the baffles and the portion above. When the parts are moved into the dotted line position then the maximum aperture 20 serves as 30 the connection.

In the normal operation of the device, the characteristic combustion method of my Patent No. 1,702,929 may be carried on. The primary air supply enters through the apertures 17 and 35 mingles with the hydrocarbon vaporized by combustion. The heat of combustion, once the device is in operation, vaporizes the hydrocarbon and the vaporized hydrocarbon rises and mixes with the primary air supply to form a primary mixture. 40 This primary mixture moves upwardly toward and through the aperture 6 of the baffle 5 and there receives the secondary air supply admitted through the apertures 16. This produces a final mixture which burns and provides the heat for 45 the stove or furnace unit.

Preferably, whether by natural draft or by any suitable fan or the like, not herein shown, sufficient air is admitted for maintaining combustion at a rate sufficient to give the desired heat. Any 50 suitable control means, thermostatic or otherwise, may be employed for controlling the desired heat produced.

In the event that it is desired to turn down the unit to a minimum heat, or to practically no 55

heat, the air supply is reduced and combustion is correspondingly reduced. In a structure such as that shown in my Patent No. 1,702,929 there is a limit below which the stove does not operate efficiently. For example, unless a sufficient air supply and sufficient rate of combustion is maintained, the secondary air or the air above the baffle 5 tends to eddy back and circulate down into the primary combustion zone, with the result that the balance between the primary and secondary zones is destroyed and my method of combustion is interrupted, resulting in carbon deposit and inefficient combustion.

In practice, the smaller the effective opening of the baffle 21, the lower is the possible minimum flame, and the greater the possible turn down of the pilot light or minimum flame thereby produced. I find that in practice there is a critical point in the size of the aperture, taken in connection with the position of the baffle or its height from the bottom of the chamber, at which the aperture is adequate to support pilot light combustion when ignition has already begun, but is insufficient to support ignition when the device is being initially lighted. However, in order to obtain a sufficient turn down, it is important to be able to locate the baffle so low in the chamber and with so small a central aperture as to make the initiation of combustion difficult or impossible when the baffle is in the horizontal position in which it is shown in Figure 1.

I find, however, that by making the baffle movable or rotatable in order to permit the effective aperture to be increased, this difficulty is overcome. Thus, when initiating combustion with the structure herein shown, the baffle 21 can be tilted into the dotted line position of Figure 1 or some intermediate position between the dotted line and full line positions. Liquid fuel is then admitted to the bottom of the combustion chamber and ignition is started by dropping a lighted match, lighted piece of paper or the like into the bottom of the burner.

With the baffle 21 in its tilted position there is ample air to support initial combustion. As soon as the oil is initially ignited and gasification has begun, the operator can then tilt the baffle 21 into horizontal or almost horizontal position and the device is then ready for normal operation. Even though the oil is then cut down to a minimum flow, the device will burn with little if any free carbon. Thus I permit the operator to have the benefit, in a single burner, of a readily lightable device which, when once lighted, can be turned down to a minimum flame and to a minimum fuel consumption.

I find that the interposition of the baffle herein shown at 19, 21 prevents this down draft and my primary mixing and combustion may be carried on by means of the holes 18. Some or all of the holes 17 then serve to provide the secondary air. In other words, when the parts are in the full line position of Figure 1 the primary air zone is moved down to or limited to the lower holes 18 below the baffle and the holes above the baffle which previously operated as a source of primary air then become a source of secondary air. This change is made in response to rotation of the central portion 21 of the baffle by use of the handle 27. When it is rotated from the full line to the dotted line position an increased supply of air enters the space below the baffle 19. This increased supply of air may be employed at the time of initiation of combustion. Thereafter, if a low flame is desired or in effect a pilot light,

the parts are restored to their full line position and there is a minimum air connection between the two chambers. This chokes down in effect the combustion and changes the function of the first three rows of apertures above the baffle 19 from that of primary air supply to that of secondary air supply.

It will be realized that whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic rather than as limiting me to my precise showing.

I claim:

1. A mechanism for burning liquid fuel which includes a chamber and means for admitting a liquid fuel to the bottom thereof, a wall for said chamber provided with a plurality of air apertures positioned above the level of the liquid fuel, and a baffle ring rotatably positioned in said chamber intermediate the top and bottom thereof for rotation about a generally horizontal axis, said ring having a central aperture, and a fixed baffle ring having an aperture conforming generally to the periphery of the movable ring and lying generally in the plane of the axis of rotation of said movable ring.

2. A mechanism for burning liquid fuel which includes a chamber and means for admitting liquid fuel to the bottom thereof, a wall for said chamber provided with a plurality of air apertures positioned above the level of the liquid fuel, a baffle member located in said chamber intermediate the upper and lower of said apertures, an aperture in said baffle member, and means for varying the effective cross sectional area of said aperture.

3. A mechanism for burning liquid fuel which includes a chamber having a wall with air admission apertures therein, means for admitting a liquid fuel to the bottom of the chamber, said chamber having an open top, a baffle normally located in the lower half of the chamber but above the lowest of said apertures, said baffle having an aperture therein, the size of the aperture in relation to the form and cubic content of the chamber and the height of the baffle from the chamber bottom being of sufficient size to maintain combustion within the portion of the chamber below said baffle, after combustion has been initiated, but being insufficient to permit combustion to be initiated, and means for admitting an excess supply of air, including means for rotating said baffle about a horizontal axis intersecting the central vertical axis of the chamber.

4. A mechanism for burning a liquid fuel which includes a chamber having a wall provided with air inlet apertures located at various levels, means for admitting a liquid fuel to said chamber, the chamber having an open top, means for dividing the chamber into an upper and a lower sub-chamber having a communicating aperture, some of the air inlet apertures communicating with the upper and some with the lower sub-chamber, and means for varying the cross-sectional area of the communicating aperture between said sub-chambers.

5. A mechanism for burning a liquid fuel which includes a chamber having a wall with air admission apertures therein, means for admitting a liquid fuel to the chamber, said chamber hav-

ing an open top, a fixed baffle located intermediate the top and bottom of said chamber and intermediate the highest and lowest of the air admission apertures, said baffle having a central aperture, a movable baffle located in said aperture, and means for changing the position of the movable baffle in said aperture.

5. A mechanism for burning a liquid fuel which includes a chamber having a wall with air admission apertures therein, means for admitting

a liquid fuel to the chamber, said chamber having an open top, a fixed baffle located intermediate the top and bottom of said chamber and intermediate the highest and lowest of the air admission apertures, said baffle having a central 5 aperture, a centrally apertured movable baffle located in said aperture, and means for changing the position of the movable baffle in said aperture.

JAMES L. BREESE. 10
